Primary Examiner — Catherine Ho*Assistant Examiner* — Tyenne A. Fulton-Crosson(74) Attorney, Agent, or Firm — Howson & Howson LLP(57) CLAIM

The ornamental design for a task chair, as shown and described.

DESCRIPTION

FIG. 1 is a top right front perspective view of a task chair showing our new design;

FIG. 2 is a top left rear perspective view thereof;

FIG. 3 is a right rear perspective view thereof;

FIG. 4 is a left front perspective view thereof;

FIG. 5 is a right side elevational view thereof, the left side elevation view being a mirror image thereof;

FIG. 6 is a front elevational view thereof;

FIG. 7 is a rear elevational view thereof;

FIG. 8 is a top plan view thereof; and,

FIG. 9 is a bottom plan view thereof.

The broken lines in the figures illustrate portions of the article which form no part of the claimed design.
